UNITED STATES PATENT OFFICE.

MORRIS P. HOLMES, OF CLAREMONT, NEW HAMPSHIRE, ASSIGNOR TO SULLIVAN MACHINE COMPANY, A CORPORATION OF MASSACHUSETTS.

MINING MACHINE.

Application filed December 19, 1924, Serial No. 757,031. Renewed April 12, 1928.

My invention relates to mining machines. An object of my invention is to provide an improved mining machine. A further object of my invention is to provide a mining machine of improved and very compact construction especially adapted to use in mines having narrow or low veins. A still further object of my invention is to provide an improved mining machine of the self-propelled, 10 flexibly fed type having improved feeding means therefor. Still another object of my invention is to provide an improved mining machine of the pivoted bar type having improved cutter chain driving connections.

15 A still further object of my invention is to provide an improved mining machine of the invertible type adapted to operate selectively as an overcutter or an undercutter. Still another object of my invention is to provide 20 an improved self-propelled flexibly fed mining machine having improved variable speed transmission mechanism between the driving motor and the feed operating member. These and other objects and advantages of 25 my invention will, however, hereinafter more fully appear.

In the accompanying drawings I have shown for purposes of illustration one embodiment which my invention may assume in 30 practice.

In these drawings,—

Fig. 1 is a plan view, partially broken away in section, of a longwall mining machine constructed in accordance with an illustrative embodiment of my invention, the cutter bar being shown in a plurality of positions.

Fig. 2 is a side elevation of the machine shown in Fig. 1, a part of the machine frame being broken away to facilitate illustration.

Fig. 3 is an enlarged vertical, longitudinally extending, developed sectional view through the improved feeding mechanism, the view being taken substantially on line 45 3—3 of Figs. 1 and 4.

Fig. 4 is a transverse vertical sectional view taken substantially on line 4—4 of Figs. 1 and 3.

Fig. 5 is a detail view of a modified form 50 of the change speed gears.

Fig. 6 is a detail view partially in section of a portion of the feed clutch controlling mechanism.

Fig. 7 is a detail sectional view taken substantially on line 7—7 of Fig. 1 through the

feed controlling handle and its cooperating parts.

Fig. 8 is a vertical longitudinally extending view through the cutter chain driving mechanism illustrating my improved controlling clutch, the view being taken substantially on line 8—8 of Fig. 1.

Fig. 9 is a transverse vertical sectional view through the clutch operating mechanism taken substantially on line 9—9 of Figs. 2 65 and 8.

Fig. 10 is an enlarged end elevation of the feeding end of the machine.

Fig. 11 is a detail view of a portion of the cutter chain clutch controlling mechanism. 70

In this illustrative construction I have shown my invention incorporated in a mining machine of the electric driven, self-propelled, 75 flexibly fed longwall type adapted to slide on its bottom on the mine bottom and having an invertible elongated frame 1 presenting parallel plane surfaces 2 and 3 upon which the machine is selectively adapted to slide during operation, that is, when the machine is being used as an undercutter or an overcutter. The machine frame 1 carries at one end a horizontal cutter bar 4 provided with the usual endless cutter bit carrying cutter chain 5, the bar being pivoted on a vertical axis, as at 6, on the rear end of the frame. The mining machine 80 is herein also adapted to be moved longitudinally along the face of the coal relative to a flexible feeding means of any suitable form, herein including a flexible feeding member or chain 7 adapted to cooperate with a feed operating member or chain sprocket 8 rotatable on a longitudinally extending horizontal axis on the front end of the machine frame 1. The machine frame 1 further comprises a motor section 9, a cutting mechanism carrying section 10, and a feed section 11 and these sections are rigidly secured together in any suitable manner, the motor section 9 being interposed between the cutter carrying section 10 and the feed section 11, in a well known manner.

90 In my improved construction it will be observed that the motor casing 9 houses an electric driving motor 12, herein of the usual reversible type, provided with a horizontally disposed, longitudinally extending armature shaft 13. In specifically describing my improved cutter chain driving mechanism it will be noted that the rear end of the armature shaft 13 has suitably secured thereto, 100

105 Fig. 8 is a detail view of a modified form of the change speed gears.

Fig. 9 is a detail view partially in section of a portion of the feed clutch controlling mechanism.

Fig. 10 is a detail sectional view taken substantially on line 7—7 of Fig. 1 through the

as by a key and nut and washer connection 14, a spur pinion 15, journaled in a bearing 16 within the frame section 9. As illustrated, the pinion 15 is internally bored, as at 17, to receive a ball bearing 18 within which, and a bearing 19 carried by the frame section 10, a shaft 20 is journaled disposed coaxial with the armature shaft 13. The shaft 20 has secured thereto, as by a key 21, a spur gear 22 disposed coaxially with the armature shaft and which gear is adapted to be connected, by means of an internal coaxial shipper gear 23, in driving relation with the pinion 15. The shipper gear 23 is adapted to be actuated longitudinally by means of a shipper yoke 24, in the form of a bell-crank, pivoted at 25 on the machine frame section 10 and provided with arms 26 and 27 adapted to cooperate with the shipper gear 23 and a bifurcated member 28, respectively. The bifurcated member 28 is adapted to engage a vertical pin 29 upon the arm 27 and is suitably carried by a cylindrical member 30 slidably mounted within a sleeve 31 mounted within a transversely disposed bore 32 formed in the side of the frame section 10. Moreover, the sleeve 31 has secured thereto, as by radially extending studs 33, an operating member or grasping portion 34 and one of the studs 33 is provided with an inwardly projecting portion 35 adapted to cooperate with a cam slot 36 formed within the member 30. Furthermore, the member 30 is provided with an upstanding portion 37 having secured, as at 38, within its upper end a transversely disposed rod 39 which is in turn secured at its opposite end, as by a screw 40, within the upper upstanding portion formed on a cylindrical member 41 similar to the member 30, the member 41 being slidably disposed within a cylindrical sleeve 42 rotatably mounted within a bore 43 coaxial with the bore 32 and formed on the opposite side of the frame section. The sleeve 42 has likewise secured thereto a grasping portion 44 as by radially disposed studs 45. It will thus be seen that the operator may operate the clutch from either side of the machine by transposition of the stud having the projecting cam slot engaging portion 35. It will herein be noted that by rotating either of the members 24 or 44 the member 30, the rod 39, and the member 41 will slide transversely of the machine relative to the sleeves 31 and 42 and the shipper yoke 24 is consequently swung about its pivot 25, thus connecting or disconnecting the shipper gear 23 with respect to the drive pinion 15 and the gear 22. As illustrated, the shaft 20 has formed thereon a bevel pinion 47 which meshes with a bevel gear 48 rotatable in a horizontal plane on a vertically disposed axis 49 and has secured thereto a spur pinion 50 rotatable in a horizontal plane above the plane of the bevel gear 48 and which pinion 50 meshes with a large spur gear 51 which has suitably rigidly

secured thereto, at its lower end, a usual sprocket 52 adapted to cooperate with and drive the cutter chain 5, in a well known manner.

In my improved feeding mechanism it will herein be observed that the forward end of the armature shaft 13 is journaled within bearings 53 within the frame section 9 and has secured thereto, as by a key and nut and washer connection 54, a driving pinion 55 which is adapted to drive the feed operating member 8 through improved transmission mechanism, to be hereinafter described, at a slow speed in one direction and at a fast speed in an opposite or reverse direction. In specifically considering the fast feed mechanism it will be noted that the pinion 55 meshes with a spur gear 56 keyed to a horizontal longitudinally disposed shaft 57 journaled in suitable bearings 58 carried by a ring section 59 receivable in a corresponding longitudinally disposed and centrally located bore 60 extending throughout the length of the frame section 11. This ring section 59 is adapted to be inserted or removed longitudinally from the rear end of the frame section 11 and has herein, preferably a cut away portion 61 to permit free rotation of the gear 56, a web portion 62 in which one of the bearings 58 is carried, and a hub portion 63 in which a bearing 64 for one end of a longitudinally disposed horizontal main feed driving shaft 65 is supported. As shown, the shaft 57 and the gear 56 are suitably located relative to the bearings 58 by suitable bearing washers and the shaft has one end projecting from one bearing and carrying a pinion 66 thereon which in turn meshes with a larger internal gear 67, the pinion and bearing being held in assembled relation by a suitable bolt connection 68. The hub 69 of the gear 67 is herein also journaled on a suitable bearing sleeve 70 on a sleeve clutch member 71 keyed, as at 72, to the shaft 65. Moreover, it will be noted that the member 71 carries a series of friction disks 73 surrounding the member 71 and disposed within a sleeve on the internal gear 67, which disks cooperate with a corresponding series of disks 75 carried by the sleeve on the internal gear. As shown, the sleeve on the internal gear is also provided with a plurality of radially located longitudinally extending slots 76 receiving radial fingers 77 on an interlocking member 78 keyed to a pinion 79 which is in turn freely rotatable on the shaft 65. Between these fingers 77 are friction clutch operating fingers 80 carried by a cylindrical plane member 81 disposed coaxially with the hub of the gear 79. These fingers 80 extend longitudinally in contact with one set of the friction disks 73 and 75. As shown, the opposite end of the shaft 65 is also journaled in a suitable ball bearing 82 carried in the hub 83 of a ring section 84, similar to the section 59, and a pin-

ion 85, similar to the pinion 79, is keyed to the shaft at a point adjacent the bearing 82. This pinion, in turn, meshes with a gear 86 keyed to a horizontal longitudinally extending shaft 87 journaled in suitable ball bearings 88. The shaft 87 carries on a projecting end a pinion 89 which meshes with an internal gear 90 disposed coaxially with the shaft 65. This internal gear 90 is in turn keyed, as 10 at 91, to a horizontally disposed longitudinally extending shaft 92 journaled within suitable longitudinally spaced roller bearings 93 carried by the feed frame section 11 and this shaft is disposed coaxially with the 15 shaft 65 and in front thereof. The forward end of the shaft 92 has secured thereto, as by a key, the feed operating member or chain sprocket 8. Thus it will be noted that the rotation of the armature shaft 13 will be 20 transmitted to the pinion 55, gear 56, pinion 66, internal gear 67, friction clutch disks 73, 75, clutch member 71, shaft 65, pinion 85, gear 86, pinion 89, internal gear 90, and shaft 92, to the feed operating member 8 to rotate 25 the latter at a predetermined high or fast feed speed whenever the clutch controlling member 81 is operated to connect the clutch. It will here further be evident that the speed of feed may be lowered at will by slipping 30 of the friction disks 73, 75.

Referring specifically to the slow or cutting feed, it will be noted that when the clutch operating member 81 is in inoperative position and the clutch is released, power will still 35 be transmitted to the interlocking member 78 through the pinion 79 which is freely rotatable on the shaft 65. This pinion, in turn, meshes with a spur gear 94 carried on a shaft 95 similar to the shafts 57 and 87 40 and journaled within bearings 96 carried within a ring section 97 similar to the ring sections 59 and 84, and likewise carried in the bore 60 and spaced from the ring section 59 by means of an intermediate spacing section 98. As illustrated, the hub of the ring section 97 carries a roller bearing 98 for the shaft 65 and it will be noted that the shaft 95 carries a pinion 99 meshing with a spur gear 100 keyed to a sleeve formed on a spur 50 pinion 101 disposed coaxially with the shaft 65 and freely rotatable relative thereto and this pinion meshes with a spur gear 102 journaled on a horizontal longitudinally extending shaft 103 similar to the shaft 95 and disposed coaxially therewith. The shaft 103 has secured thereto at its forward end a spur pinion 104 which meshes with a large internal gear 105 substantially similar to the internal gear 67. The internal gear 105 also houses a 55 friction clutch substantially similar to the clutch heretofore described in connection with clutch disks 73, 75 and this clutch includes clutch disks 106 and 107 certain of which are carried on a clutch member 108 60 keyed, as at 109, to the shaft 65, while others 65 are carried by a sleeve formed on the internal gear 105. An intermediate member 110 is keyed to the sleeve formed on the pinion 85 and a plane clutch operating member 111 surrounds the hub of the clutch member 110, 70 the latter of which in this instance has no interlocking function and is only a spacing and disk retaining member. A ring section 112 and a spacing member 113, similar to the spacing member 98, are disposed between 75 the ring member 97 and the ring member 84, the ring member 112 carrying a ball bearing 114 within which the shaft 65 is further journaled. It will herein be noted that all of these ring sections are non-rotatably secured 80 in the bore 60 in any suitable manner. As a result of this mechanism above described, although the clutch 73, 75 is disconnected, rotation will constantly be imparted through the pinion 79, gear 94, pinion 99, gear 100, pinion 85 85 101, gear 102, pinion 104, internal gear 105, clutch disks 106, 107, clutch member 108, shaft 65, pinion 85, gear 86, pinion 89, internal gear 90, and shaft 92 so that when the clutch 106, 107 is connected the feed 90 operating member 8 will be rotated at a slow or cutting speed in the opposite or reverse direction from the fast speed previously described. Here it will also be evident that by slipping the friction 106, 107 this speed may 95 also be reduced when desired. It will herein be understood that in my improved construction the gears 79 and 94 are change speed gears. These gears may be removed and replaced by other sets of gears 79^a and 94^a, (see 100 Fig. 5) the ratio of the gear teeth being so varied that the feed operating member 8 may be rotated at a considerable range of slow or cutting speeds, herein from a feeding speed of approximately 18 inches a minute 105 especially adapted for hard cutting to a speed of approximately 51 inches a minute especially adapted for soft cutting, and in certain cases even higher or lower speeds may be obtained. It will also be noted that if desired 110 the ratio of the teeth of the gears 101 and 102 may likewise be varied and the speed further varied.

Operatively associated with the feeding mechanism above described, are pivoted 115 clutch shipper members 115 and 116 (see Fig. 1) provided at one end with suitable rollers 117 adapted to engage the plane surfaces of the clutch operating members 81 and 111, respectively. The outer ends of these shippers 120 are also provided with rectangular portions 117 and 118 having arcuate engaging surfaces which register with slots 119 and 120, respectively, formed in slidably engageable parallel rods 121 and 122 suitably guided in 125 the machine frame at their opposite ends. These rods are grooved or cut away at 123 and 124 to permit longitudinal relative movement therebetween and are provided at their forward ends with annular semi-circular screw 130

portions 125 and 126 which have threads 127 and 128 of opposite pitch and which are adapted to engage a nut 129 having threads of opposite pitch which engage the threads 5 on the members. The nut 129 has secured thereto a grasping or operating portion 130 disposed contiguous to the forward end of the machine frame adjacent the feed operating member 8. It will be observed that by rotating the handle 130 and consequently the threaded nut 129 engaging the threads formed on the rods 121 and 122 will cause the latter to simultaneously move in opposite directions and causing one of the friction mechanisms to 15 be released while the other is applied, thereby preventing the simultaneous applications of two feeds, i. e. the fast and slow speeds.

As illustrated, guide sprockets 131, 132, 133, and 134 are disposed on vertically disposed 20 parallel axes at the sides of the feed operating member 8 and are adapted to guide the feed chain 7 relative to the feed operating member 8 during the various operations of the machine, in a well known manner.

25 While I have in this application specifically described one embodiment which my invention may assume in practice, it will be understood that this form of the same is shown for purposes of illustration and that 30 the invention may be modified and embodied in various other forms without departing from its spirit or the scope of the appended claims.

What I claim as new and desire to secure 35 by Letters Patent is:

1. In a mining machine, a driving motor having a horizontal armature shaft extending longitudinally of the machine, and feeding means driven by said motor including a feed 40 operating member adapted to cooperate with flexible feeding means, and a plural speed driving mechanism therefor having a driving gear for each speed disposed coaxially with said armature shaft, said last mentioned 45 gears and all the other gears of said mechanism being rotatable on axes extending longitudinally of the machine.

2. In a mining machine, a driving motor having a horizontal armature shaft extending 50 longitudinally of the machine and disposed in the central longitudinal vertical plane of the latter, and feeding means driven by the adjacent end of said motor including a feed operating member adapted to cooperate with 55 flexible feeding means, and a plural speed driving mechanism therefor, the gears of said mechanism being all disposed on axes parallel to a line parallel with said armature shaft axis.

60 3. In a mining machine, a driving motor having a horizontal armature shaft extending longitudinally of the machine, and feeding means for the machine driven by said motor including a feed operating member

adapted to cooperate with flexible feeding means, and a plural speed driving mechanism therefor including a plurality of internal gears coaxial with said armature shaft. 65

4. In a mining machine, a driving motor having a horizontal armature shaft extending longitudinally of the machine, and feeding means for the machine driven by said motor including a feed operating member adapted to cooperate with flexible feeding means, and a plural speed driving mechanism including a plurality of internal gears coaxial with said armature shaft, one speed driving through one of said gears while another speed drives through both of said gears. 70 75

5. In a mining machine, a driving motor having a horizontal armature shaft extending longitudinally of the machine and disposed in the central longitudinal vertical plane of the latter, and feeding means for the machine driven by said motor including a feed operating member adapted to cooperate with flexible feeding means, and a plural speed driving mechanism including selectively operable fast and slow speed clutches arranged coaxially with said feed operating member, all the driving gearing of said mechanism being arranged on axes parallel to a line parallel with said armature shaft axis. 80 85

6. In a mining machine, a driving motor having a horizontal armature shaft extending longitudinally of the machine and disposed in the central longitudinal vertical plane of the latter, and feeding means for the machine driven by said motor including a feed operating member adapted to cooperate with flexible feeding means, and a plural speed driving mechanism including a plurality of internal gears coaxial with said feed operating member. 90 95 100

7. In a mining machine, a driving motor having a horizontal armature shaft extending longitudinally of the machine and disposed in the central longitudinal vertical plane of the latter, and feeding means for the machine driven by said motor including a feed operating member adapted to cooperate with flexible feeding means, and a plural speed driving mechanism including a plurality of internal gears coaxial with said feed operating member, one speed driving through one of said gears while another speed drives through both of said gears. 105 110 115

8. In a mining machine, a driving motor having a horizontal armature shaft extending longitudinally of the machine, and feeding means for the machine driven by said motor including a feed operating member adapted to cooperate with flexible feeding means and arranged coaxially with said armature shaft, and a plural speed driving mechanism including a plurality of selectively operable fast and slow speed clutches arranged coaxially with said feed operating 120 125

member, and driving gearing rotatable on axes parallel to a line parallel with said armature shaft axis.

9. In a mining machine, a motor having a horizontal armature shaft extending longitudinally of the machine and disposed in the central longitudinal vertical plane of the latter, feeding means driven by said motor including a feed operating member adapted to cooperate with flexible feeding means, and feed driving mechanism including change speed gearing having its driving gear coaxial with said armature shaft and its driven gear disposed on a parallel axis, all of the gearing of said driving mechanism being arranged on horizontal axes extending longitudinally of the machine.
10. In a mining machine, a motor having a horizontal armature shaft extending longitudinally of the machine, feeding mechanism driven by said motor including a feed operating member adapted to cooperate with flexible feeding means, and feed driving mechanism including change speed gearing having its driving gear coaxial with said feed operating member and said armature shaft and its driven gear disposed on a parallel axis, all of the gearing of said driving mechanism being rotatable on horizontal axes extending longitudinally of the machine.

11. In a mining machine, a motor having a horizontal armature shaft extending longitudinally of the machine, and feeding mechanism driven by said motor including a feed operating member adapted to cooperate with flexible feeding means and disposed coaxially with said armature shaft, and feed driving mechanism including change speed gearing having its driving gear coaxial with said feed operating member and its driven gear disposed on a parallel axis, all the gearing of said driving mechanism being rotatable on horizontal axes extending longitudinally of the machine.

12. In a mining machine, a motor having a horizontal armature shaft extending longitudinally of the machine and disposed in the central longitudinal vertical plane of the latter, and feeding mechanism driven by said motor including a feed operating member adapted to cooperate with flexible feeding means and rotatable on an axis extending longitudinally of the machine, and feed driving mechanism disposed coaxially with said feed operating member including change speed gearing having its driving gear coaxial with said feed operating member and its driven gear disposed on a parallel axis, all the gearing of said driving mechanism being rotatable on horizontal axes extending longitudinally of the machine.

13. In a mining machine, a driving motor having a horizontal armature shaft extending longitudinally of the machine and having means driven by said motor including a

feed operating member adapted to cooperate with flexible feeding means, and a plural speed driving mechanism therefor having a driving gear for each speed disposed coaxially with said armature shaft, said driving gears being relatively rotatable, and fast and slow speed clutches for selectively connecting said gears in driving relation with said feed operating member.

14. In a mining machine, a driving motor having a horizontal armature shaft extending longitudinally of the machine and disposed in the central longitudinal vertical plane of the latter, and feeding means driven by said motor including a feed operating member adapted to cooperate with flexible feeding means and rotatable on an axis extending longitudinally of the machine, and a plural speed driving mechanism therefor having a driving gear for each speed arranged coaxially with said feed operating member and fast and slow speed clutches for selectively connecting said gears in driving relation with said feed operating member.

15. In a mining machine, a driving motor having a horizontal armature shaft extending longitudinally of the machine, and feeding means driven by said motor including a feed operating member adapted to cooperate with flexible feeding means, and a plural speed driving mechanism therefor having a driving gear for each speed and fast and slow speed clutches all arranged coaxially with said armature shaft for selectively connecting said gears in driving relation with said feed operating member.

16. In a mining machine, a driving motor having a horizontal armature shaft extending longitudinally of the machine and disposed in the central longitudinal vertical plane of the latter, and feeding means driven by said motor including a feed operating member adapted to cooperate with flexible feeding means and rotatable on an axis in a vertical plane extending longitudinally of the machine, and a plural speed driving mechanism therefor having a driving gear for each speed and fast and slow speed clutches arranged coaxially with said feed operating member for selectively connecting said gears in driving relation with said feed operating member.

17. In a mining machine, a driving motor having a horizontal armature shaft extending longitudinally of the machine, and feeding means driven by said motor including a feed operating member adapted to cooperate with flexible feeding means, and a plural speed driving mechanism therefor having a driving gear for each speed, said gears being arranged on aligned axes, and fast and slow speed clutches arranged coaxially with said armature shaft for selectively connecting said gears in driving relation with said feed operating member.

18. In a mining machine, a driving motor having a horizontal armature shaft extending longitudinally of the machine, and feeding means driven by said motor including a feed 5 operating member adapted to cooperate directly with flexible feeding means and arranged coaxially with said shaft, and plural speed driving mechanism therefor including alined driving gears rotatable in opposite directions and fast and slow speed clutches for selectively connecting said gears in driving relation with said feed operating member to drive the latter at different speeds in opposite directions.
19. In a mining machine, a driving motor having a horizontal armature shaft extending longitudinally of the machine, and feeding means driven by said motor including a feed operating member adapted to cooperate 10 directly with flexible feeding means, and a plural speed driving mechanism therefor including relatively rotatable driving gears arranged coaxially with said shaft and rotatable in opposite directions and fast and slow speed clutches for selectively connecting said gears in driving relation with said feed operating member to drive the latter in opposite directions at different speeds.
20. In a mining machine, a driving motor having a horizontal armature shaft extending longitudinally of the machine, and feeding means driven thereby including a feed operating member adapted to cooperate directly with flexible feeding means and a plural speed driving mechanism therefor including fast and slow speed driving gears rotatable on axes alined with said shaft and rotatable in opposite directions, all of the gears of said mechanism rotating on axes extending 25 longitudinally of the machine.
21. In a mining machine, a driving motor, cutting mechanism driven thereby, a clutch interposed between said motor and mechanism and operable to effect driving of the latter, and mechanism for operating said clutch comprising an element bodily reciprocable transversely of the machine, and rotatable operating members disposed at opposite sides of the machine and operatively connectible directly to said reciprocable element to effect, on rotation, reciprocation of the latter.
22. In a mining machine, a driving motor, cutting mechanism driven thereby, a clutch 30 interposed between said motor and mechanism and operable to effect driving of the latter, and mechanism for operating said clutch comprising an element bodily reciprocable transversely of the machine and having cam surfaces, and rotatable operating members disposed at opposite sides of the machine and one of said operating members engaging one of said cam surfaces.
23. In a mining machine, a driving motor, cutting mechanism driven thereby, a clutch 35

interposed in the drive between said motor and mechanism including an element coaxial with the axis of said motor, and mechanism for operating said clutch comprising an element bodily reciprocable transversely of the machine, and rotatable operating members disposed on opposite sides of the machine and operatively connectible to said reciprocable element to effect, on rotation, reciprocation of the latter. 75

24. In a mining machine, a driving motor, cutting mechanism driven thereby, a clutch interposed between said motor and mechanism and operable to effect driving of the latter, and mechanism for operating said clutch comprising a rod reciprocable transversely of the machine and secured at its opposite ends to elements having cam surfaces, and rotatable operating members disposed at opposite sides of the machine and one of said operating members engaging one of said cam surfaces. 80

25. In a mining machine, a driving motor having a horizontal armature shaft extending longitudinally of the machine, cutting mechanism driven thereby, a clutch interposed between said motor and mechanism and operable to effect driving of the latter, and mechanism for operating said clutch comprising a rod reciprocable transversely of said armature shaft, and manually operable rotatable members disposed at opposite sides of the machine and operatively connectible to said reciprocable rod to effect, on rotation, reciprocation of the latter. 90

26. In a mining machine, a machine frame, a driving motor, cutting mechanism driven thereby, a clutch interposed between said motor and mechanism and operable to effect driving of the latter, and mechanism for operating said clutch comprising a rod reciprocable transversely of the machine frame, members connected at the opposite ends of said rod and having cam surfaces, and manual operating members rotatably mounted in said frame at opposite sides of the machine and one of said operating members engaging one of said cam surfaces. 100

27. In a mining machine, a machine frame, a driving motor, cutting mechanism driven thereby, a clutch interposed in the drive between said motor and mechanism including a reciprocable clutch element coaxial with the motor axis, a shipper yoke cooperating with said element, a rod reciprocable transversely of the machine, members connected to the opposite ends of said rod and having cam surfaces, one of said members being connected to said shipper yoke, and manual operating members rotatably mounted in the machine frame at opposite sides of the machine and one of said operating members engaging one of said cam surfaces. 110

28. In a mining machine, a machine frame, a driving motor, cutting mechanism driven 120

- thereby, a clutch interposed in the drive between said motor and mechanism including a reciprocable clutch element coaxial with the motor axis, a shipper yoke pivoted on a vertical axis and cooperating with said element, a rod reciprocable transversely of the machine, members connected to the opposite ends of said rod and having cam surfaces, one of said members being connected to said shipper yoke, and manual operating members rotatably mounted in the machine frame at opposite sides of the machine and one of said operating members engaging one of said cam surfaces.
29. In a mining machine, a driving motor, cutting mechanism driven thereby, a clutch interposed in the drive between said motor and mechanism including a clutch element coaxial with the axis of said motor, and mechanism for operating said clutch including cam operated elements reciprocable bodily transversely of the machine and rotatable operating elements disposed at opposite sides of the machine and one of said operating elements operatively engaging one of said cam operated elements.
30. In a mining machine, a driving motor, cutting mechanism driven thereby, a clutch interposed in the drive between said motor and mechanism including a clutch element coaxial with the motor axis, and mechanism operable from either side of the machine for operating said clutch comprising an element bodily reciprocable transversely of the machine and having a cam surface and a manually rotatable element engaging said cam surface and operative on rotation to effect reciprocation of said reciprocable element.
31. In a mining machine, a driving motor, cutting mechanism driven thereby, a clutch interposed in the drive between said motor and mechanism including a clutch element coaxial with the motor axis, and mechanism operable from either side of the machine for operating said clutch comprising a bodily reciprocable element, and a manually operable rotatable element operatively connected to said reciprocable element.
32. In a mining machine, a driving motor having a horizontal armature shaft extending longitudinally of the machine, and feeding means driven by said motor including a feed operating member adapted to cooperate with flexible feeding means and arranged coaxially with said armature shaft, and plural speed transmission means between said shaft and feed operating member, all of the gears of said transmission means rotating on axes extending longitudinally of the machine.
33. In a mining machine, a driving motor having a horizontal armature shaft extending longitudinally of the machine, and feeding means driven by said motor including a feed operating member adapted to cooperate with flexible feeding means, and plural speed transmission means between said shaft and feed operating member including fast and slow speed controlling clutches arranged coaxially with said shaft, all of the gears of said transmission means rotating on axes extending longitudinally of the machine.
34. In a mining machine, a driving motor having a horizontal armature shaft extending longitudinally of the machine, cutting mechanism driven from one end of said shaft including a pivoted cutter bar, and feeding means driven from the opposite end of said shaft including a feed operating member adapted to cooperate with flexible feeding means and arranged coaxially with said armature shaft, and plural speed transmission means between said shaft and said feed operating member.
35. In a mining machine, a driving motor having a horizontal armature shaft extending longitudinally of the machine, cutting mechanism driven from one end of said shaft including a pivoted cutter bar, and feeding means driven from the opposite end of said shaft including a feed operating member adapted to cooperate with flexible feeding means, and plural speed transmission means between said shaft and said feed operating member including fast and slow speed clutches arranged coaxially with said shaft.
36. In a mining machine, a driving motor having a horizontal armature shaft extending longitudinally of the machine, cutting mechanism driven from one end of said shaft including a pivoted cutter bar, and feeding means driven from the opposite end of said shaft including a feed operating member adapted to cooperate with flexible feeding means, and plural speed transmission means between said shaft and feed operating member including a fast speed gear train and a slow speed gear train each including a gear arranged coaxially with said shaft, said gears coaxial with said shaft being relatively rotatable.
37. In a mining machine, a driving motor having a horizontal armature shaft extending longitudinally of the machine, and feeding means driven by said motor including a feed operating member adapted to cooperate with flexible feeding means and rotatable on a horizontal axis extending longitudinally of the machine, and plural speed transmission means between said shaft and said feed operating member for effecting rotation thereof at a slow speed in one direction and at a fast speed in the opposite direction while said shaft rotates continuously in the same direction and having a gear in each speed arranged coaxially with said shaft, said gears coaxial with said shaft being relatively rotatable.
38. In a mining machine, a driving motor having a horizontal armature shaft extending longitudinally of the machine, and feeding means driven by said motor including a feed

- operating member adapted to cooperate with flexible feeding means and arranged coaxially with said shaft, and plural speed transmission means between said shaft and said feed operating member for effecting rotation thereof at a slow speed in one direction and at a fast speed in the opposite direction while said shaft rotates continuously in the same direction.
19. 39. In a mining machine, a driving motor having a horizontal armature shaft extending longitudinally of the machine, and feeding means driven by said motor including a feed operating member adapted to cooperate with flexible feeding means and rotatable on a horizontal axis extending longitudinally of the machine, and plural speed transmission means between said shaft and said feed operating member for effecting rotation thereof at a slow speed in one direction and at a fast speed in the opposite direction while said shaft rotates continuously in the same direction.

tion and including fast and slow speed controlling clutches arranged coaxially with said shaft.

25

40. In a mining machine, a driving motor having a horizontal armature shaft extending longitudinally of the machine, and feeding means driven by said motor including a feed operating member adapted to cooperate with flexible feeding means and rotatable on a horizontal axis extending longitudinally of the machine, and plural speed transmission means between said shaft and said feed operating member for effecting rotation thereof at a slow speed in one direction and at a fast speed in the opposite direction while said shaft rotates continuously in the same direction including a gear in each speed arranged coaxially with said shaft, all of the gears of said transmission means rotating on axes extending longitudinally of the machine.
